UNITED STATES PATENT OFFICE.

MANANDER M. JOHNSON, OF CLAY CENTER, NEBRASKA.

LAMP.

SPECIFICATION forming part of Letters Patent No. 712,071, dated October 28, 1902.

Application filed June 12, 1902. Serial No. 111,387. (No model.)

To all whom it may concern:

Be it known that I, MANANDER M. JOHNSON, a citizen of the United States, residing at Clay Center, in the county of Clay and State 5 of Nebraska, have invented certain new and useful Improvements in Lamps; and I do declare the following to be a full, clear, and exact description of the invention, such as will enable others skilled in the art to which it 10 appertains to make and use the same.

This invention relates to lamps, and particularly to oil-burning lamps of the character designed more especially for use in connection with incubators.

15 The object of the invention is to provide a lamp of this character in which provision is made for keeping the oil-font cool and permitting of the escape of any gases generated therein, thereby obviating all liability of the 20 gases being generated and confined to such an extent as to cause an explosion.

With these and other objects in view the invention consists in certain novel features of construction, combination, and arrangement of parts, which will be hereinafter more 25 fully set forth, and particularly defined in the appended claim.

The figure of the drawing represents a central vertical section of a lamp embodying my 30 invention.

Referring to the drawing, the numeral 1 represents a metallic bowl or font provided in its top with a central opening 2, and 3 is an annular water-reservoir superposed upon 35 said bowl and having a central tube 4 coinciding with said opening. A collar 5, mounted upon the reservoir, is threaded to receive the burner 6, which may be of any ordinary construction. The reservoir is supplied with 40 water and forms a jacket inclosing the burner to keep the bowl cool and reduce to a minimum the amount of gas generated from the heat of the lamp.

Extending upwardly through the bottom of the font and terminating adjacent to the collar 45 5 is an air-tube 7, through which air is admitted to further cool the burner. This air discharges through a vent formed by a handle 8, which is provided with the tubular legs 9 and 10, one communicating with the font and 50 the other with the water-jacket. By this means the gas generated in the font is allowed to discharge, and all vapor formed in the water-jacket is also allowed to pass off. The tubes 9 and 10 further form funnels through 55 which the oil-reservoir and jacket may be conveniently filled.

It will be seen that owing to the fact that the font is kept cool the formation of gas is reduced to the minimum, and that what little 60 gas that is permitted to form is carried off through the vent by the air from tube 7, thereby obviating all liability of an explosion.

Having thus described my invention, what 65 I claim as new, and desire to secure by Letters Patent, is—

A lamp, comprising a bowl provided with an opening in its top, a burner-supporting tube rising from said opening, a water-reservoir superposed upon the bowl and surrounding said burner-supporting tube, an air-supply tube leading to the interior of the burner-supporting tube, and a handle having tubular legs forming vents and funnels, one communicating with the bowl and the other with the water-reservoir, substantially as described.

In testimony whereof I have hereunto set my hand in presence of two subscribing witnesses.

MANANDER M. JOHNSON.
